UNITED STATES PATENT OFFICE.

WILLIAM B. HUGHES, OF WISSAHICKON, PENNSYLVANIA.

ROLLING-MILL.

SPECIFICATION forming part of Letters Patent No. 739,416, dated September 22, 1903.

Application filed April 11, 1903. Serial No. 152,148. (No model.)

To all whom it may concern:

Be it known that I, WILLIAM B. HUGHES, residing at Wissahickon, in the county of Philadelphia, State of Pennsylvania, have invented 5 certain Improvements in Rolling-Mills, of which the following is a specification.

This invention relates particularly to improvements in rolling-mill housings and yokes therefor.

10 The principle objects of the improvements are to produce housings of simplified construction and increased strength permitting the ready assemblage, adjustment, and dis- 15 sassembly of the parts and providing ready means for handling.

The characteristic features of the improvements will more fully appear by reference to the following description and the accompanying drawings, of which—

20 Figure 1 represents a side elevation and partial section of a rolling-mill embodying the improvements. Fig. 2 represents a front elevation and partial section thereof, and Fig. 3 represents a view of the top of the housings 25 and the yoke connection therewith.

As shown in the drawings, the housings 1 are provided with the angular heads 2, having the shoulders 3, which register with the respective ends of the yoke 4, having the 30 shoulders 5 for engaging the shoulders 3, the stepped offsets formed by these shoulders overlapping and holding the parts together against the upward thrust or pull on the yoke. The respective housing-heads have

35 the lugs 6 and 7, which register with the respective lugs 8 and 9 on each end of the yoke, the corresponding lugs having the pins 10 and 11 passed therethrough and drawn up by the keys 12 and 13. The vertical pins 14

40 further engage the yoke to the housing-heads and are drawn up by the keys 15. Thus the heads of the several housings are readily connected together as a unit, readily disconnected by merely knocking out the keys and

45 withdrawing the pins and readily handled by connecting the yoke with a crane. The firm and simple character of the engagement of the yoke with the housings avoids the defects and inconveniences that obtain with the usual

movable caps and integral heads heretofore employed. The housings are provided with the rabbets 16, in which are the slots 17, and the boxes or bearings 18 are engaged therewith by the bolts 19, the bearings being thereby provided with a limited movement within their ways thus formed in the housings and being readily removable outwardly from the rolls. The upper bearings have the screw-caps 20 connected therewith, and these caps are connected with the yoke 4 by the screws 21, through which the yoke and the housing-heads receive the upward thrust from the rolls 22. The rods 23, vertically reciprocated in ways in the housings by a ram 24, are adapted for lifting the lower journal-boxes 25 to permit their being lined up, the rods being provided with lugs 26 for engaging lugs 27 on the boxes. The housings are connected and supported by their feet 28 upon the ways 29, to which they are fastened by bolts 30. The yoke 4 is readily removed endwise from its engagement with the standard-heads 2 by knocking out the pins 10, 11, and 14, the caps 20 and bearings 18 having been disengaged, as by lifting the caps or withdrawing 35 the bearings.

The strength and simplicity of the construction and the readiness with which it can be assembled, dissociated, and transported will now be seen, these advantages resulting, 40 primarily, from the use of the yoke having the positive or stepped engagement with the disconnected head of the standards.

Having described my invention, I claim—

1. Housing-standards having angular disconnected heads, and a yoke positively engaged between said heads, said yoke and heads having overlapping parts to provide said engagement and prevent the upward movement of said yoke, substantially as specified. 45

2. Housings having shouldered heads, a shouldered yoke engaged between said heads, and pin connections for clamping said heads and yoke together, said heads overlapping and holding said yoke against upward movement, substantially as specified. 50

3. A set of housing-standards having disconnected heads, in combination with a sec-

ond set of housing-standards having disconnected heads, and a yoke positively engaging and uniting said standard-heads, said heads overlapping and holding said yoke against 5 upward movement, substantially as specified.

4. Housing-standards having angular disconnected heads with lugs thereon, a yoke positively engaged between said heads and having a lug thereon registering with the lugs 10 on said heads, and a pin engaging said lugs

and clamping said parts together, substantially as specified.

In testimony whereof I have hereunto set my hand, in the presence of the subscribing witnesses, this 28th day of March, A. D. 1903. 15

WILLIAM B. HUGHES.
